UNITED STATES PATENT OFFICE

152,778

DESIGN FOR AN AIR BLOWER

Wilfred R. Fox, Owosso, Mich., assignor to Redmond Company, Inc., Owosso, Mich., a corporation of Michigan

Application November 21, 1947, Serial No. 142,718

Term of patent 14 years

(Cl. D62—4)

To all whom it may concern:

Be it known that I, Wilfred R. Fox, a citizen of the United States and a resident of Owosso, in the county of Shiawassee and State of Michigan, whose post-office address is 325 N. Washington Street, Owosso, Michigan, have invented a new, original, and ornamental Design for an Air Blower, of which the following is a specification, reference being had to the accompanying drawing, forming a part thereof.

On the drawing,

Fig. 1 is a side perspective view of an air blower embodying my new design;

Fig. 2 is a side elevational view of the blower shown in Fig. 1 to a slightly enlarged scale; and

Fig. 3 is a front elevational view of the blower shown in Fig. 2.

The unillustrated side of the blower is substantially plain in appearance.

I claim:

The ornamental design for an air blower, substantially as shown and described.

WILFRED R. FOX.
